UNITED STATES PATENT OFFICE.

EDWARD STUART McDougall, OF MONTREAL, QUEBEC, CANADA.

RECEPTACLE TOP.

Application filed May 10, 1928, Serial No. 276,749, and in Canada May 14, 1927.

This invention relates to new and useful improvements in receptacle closures and particularly to receptacle closures in which are used the standard circular cardboard caps usually employed for sealing milk bottles, and the object of the invention is to provide a specially constructed receptacle top which will facilitate the opening of the receptacle without the use of picks or other 10 pronged instruments.

Another object is to provide a receptacle of the class stated which will be simple and inexpensive in construction, and in which means will be provided to hold the cap in a 15 predetermined position without handling the underside of the cap, thereby avoiding the risk of infection or contagion through such handling.

A further object is to provide a receptacle, 20 the top of which will form a perfect sealing means when used in conjunction with a resilient circular cap.

In my invention I provide a receptacle top having an internal annular shoulder or seat 25 which extends around and in close proximity to the receptacle opening. The said annular shoulder or seat is made with part of its circumference sufficiently wide to support a resilient cap and prevent it from 30 being forced into the neck of the receptacle. The remaining part of the shoulder or seat is just made of sufficient width to contact with the cap and form a seal therewith, but on reasonable pressure being applied to the 35 cap at an indicated point, said second part of the seat or shoulder will allow the cap to pivot as hereinafter described. The inner wall extending from said shoulder to the upper edge surrounding the opening, con- 40 verges towards said edge so that a resilient cap, when pressed into the top of the receptacle against the upper surface of said shoulder, will engage with the inner wall and form an efficient sealing means which 45 will allow free handling of the receptacle during transportation of same. The converging inner wall also forms a means for holding the cap in its open or pouring position. I may also provide means on the

upper edge of the receptacle to hold the cap 50 positively in position during the process of pouring the contents from the receptacle. The upper edge is also provided with means to indicate where pressure may be applied to the cap to open the receptacle. 55

In the drawings, Figure 1 is a plan view of my improved receptacle top; Figure 2 is a parital sectional elevation of the top taken on the line 2-2 Figure 1; Figure 3 is a sectional elevation of the receptacle top 60 taken on the line 3-3 Figure 1; Figure 4 is a perspective view of the receptacle top with the cap shown in the unsealed or pouring position, and Figure 5 is a perspective view of the receptacle top showing the cap supporting shoulder. 65

Referring more particularly to the drawings in which I have shown a milk bottle for illustrative purposes only, 11 designates the neck or top of the bottle, the upper edge 12 70 of which may be flat, as shown, or rounded of which may be flat, as shown, or rounded as desired. A shoulder or seat 13 is formed in the inner wall of the neck in close proximity to the edge 12, but spaced therefrom, said seat being adapted to form a support 75 for the usual circular cardboard or paper stopper, or cap 14, which is used for sealing receptacles of this class. The shoulder or seat is made of two different widths, with its maximum width 13^a extending part way 80 around the inner wall of the receptacle for a distance slightly more than half the circumference of said wall. In my preferred form, I prefer the circumferential length of the said wide part of the shoulder, or seat, to 85 be approximately equal to two-thirds the circumference of the inner wall, or to embrace an angle of from 200° to 280°. The remaining part 13^b of the shoulder or seat is made of less width than the part 13^a, so that a 90 decided step is formed between the said parts of the shoulder or ledge. The ends 15 of the wider part of the shoulder may be bevelled as shown in Figures 1 and 5, or they may be formed parallel with the longitudinal axis of the receptacle and may project inwardly from the edge of the shoulder. The ends of the wider part of the shoulder 95

form a pivoting means for the cap when the portion supported only by the narrower part of the shoulder is pressed down into the receptacle and the cap is in the open position 5 shown in Figure 4.

The portion 16 of the inner wall between the shoulder or seat and the edge 12, converges inwardly towards said edge, so that the cap, which is made of resilient material, 10 requires to be pressed into position to seal the receptacle, the edge of said cap being adapted to frictionally engage with the inner wall towards the outer edge of the ledge or shoulder and rest upon the annular 15 shoulder. It will be noted that this forms a close seal with the verging walls tending to hold the seal in position if the pressure due to weight of the milk is exerted on the cap through upturning of the bottle during 20 transportation of same.

The converging wall by frictionally engaging with the edge of the cap, may form a means for holding the cap in its open position. A star 18, or like mark, may be 25 formed in the upper edge of the receptacle to indicate the centre of the portion of the cap supported by the narrow part of the shoulder between the ends of the wider part of the seat or shoulder. I may also provide 30 recesses or grooves 17 in the inner wall in proximity to the upper edge 12, to hold the cap in its open or pouring position in a positive manner, as shown in Figure 4. Modifications may be made in the shape of the 35 neck of the bottle or receptacle without departing from the spirit of the invention.

In operation to close the receptacle, the cap is pressed into the neck until it engages or rests upon the uppermost surface of the 40 shoulder or ledge. The cap being made of cardboard, or such like resilient material, frictionally engages with the lowermost portion of the converging inner wall and forms an efficient seal which will allow rough handling or even upturning of the bottle without spilling its contents during the transportation of same. To open the receptacle, 45 pressure is applied to the edge of the cap supported by the narrow part of the seat, the position of which is indicated by the mark on the upper edge of the top. There being only enough support under the cap where pressure is applied to form a seal and not to prevent the pivoting of the cap, the 50 said portion is pressed down into the top or neck, while the remaining portion is raised by pivoting about the ends of the ledge or shoulder, as shown in Figure 5. The edge of the raised portion frictionally engages 55 with the uppermost edge of the inner wall and holds the cap in any desired position during the pouring of the contents from the bottle. In cases where recesses are 60 formed in the inner wall near the upper edge 65 of the receptacle, the cap may be pivoted

until its edge springs into said recesses to hold the cap in a predetermined position while pouring the contents of the receptacle.

It will be easily seen that there is no necessity for the operator to handle the underside 70 of the cap while opening the receptacle, and that no picks or such like instruments need be applied to the cap to lift it into the open position. This construction prevents the bottle contents from becoming infected by 75 germs carried by the hands of the operator during the process of opening the receptacle.

The device is very simple and efficient in operation and is inexpensive to manufacture, 80 as the shoulder may be formed when moulding the top of the receptacle during the manufacture of same.

It will be readily seen that the part 13^b of the seat may be modified and made flush with the inner wall of the receptacle without 85 departing from the spirit of the invention.

Having thus described my invention, what I claim is:—

1. A receptacle top having an annular seat 90 extending around the inner wall of the neck of the receptacle near the upper end thereof, the greater circumferential part of said seat being of greater width than the remaining part thereof and forming a pivoting means for the receptacle closure on each side the 95 neck, between the different widths of the seat, said inner wall converging from said seat towards the upper edge of the receptacle.

2. A receptacle top having an annular seat 100 extending around the inner wall of the receptacle neck near the upper end thereof, the greater part circumferentially of said seat being of greater width than the remaining part, the junction between said parts forming shoulders about which a closure cap may be pivoted, said shoulders being adapted to project into the neck of the bottle, said inner wall converging from said seat towards the 105 upper edge of the receptacle.

3. A receptacle closure comprising a receptacle having a seat extending around the inner wall thereof, said seat being made in two widths, the larger width extending for a distance equal to more than half the circumference of the wall, said seat being positioned in close proximity to the opening of the receptacle, a plurality of recesses formed in said inner wall in proximity to the junction between the wider and narrower parts 115 of the seat, and a closure member adapted to lie flat against the seat in the closed position and to engage with the said recesses when in the open position.

4. A receptacle closure comprising a receptacle top having an inner annular seat near the upper edge thereof, said seat being made in two widths, the larger width extending for a distance equal to more than half the circumference of the inner wall of 120

the neck, a plurality of recesses formed in the upper edge in proximity to the junction between the wider and the narrower parts of the seat, said inner wall converging from the 5 seat towards the upper edge of the receptacle, and a resilient cap adapted to lie flat on said seat when in its closed position and

to engage with the recesses in the upper edge when in the open position, and means to indicate where pressure is to be applied to the 10 cap to facilitate opening of same.

In witness whereof, I have hereunto set my hand.

E. STUART McDougall.
